UNITED STATES PATENT OFFICE

108,575

DESIGN FOR AN ALUMINUM ALLOY INGOT OR THE LIKE

Henry Lindenberger, Chicago, Ill., assignor to
U. S. Reduction Co., East Chicago, Ind., a cor-
poration of Illinois

Application August 25, 1937, Serial No. 71,311

Term of patent 14 years

To all whom it may concern:

Be it known that I, Henry Lindenberger, a citizen of the United States, residing in Chicago, in the county of Cook and State of Illinois, have invented a new, original, and ornamental Design for an Aluminum Alloy Ingot or the like, of which the following is a specification, reference being had to the accompanying drawing, forming a part thereof.

Fig. 1 is a top plan view of an aluminum alloy ingot or the like showing my new design;

Fig. 2 is a side elevational view; and

Fig. 3 is a sectional view taken on the line 3—3 of Fig. 1.

I claim:

The ornamental design for an aluminum alloy ingot or the like as shown.

HENRY LINDENBERGER.
